UNITED STATES PATENT OFFICE.

WILLIAM P. AIKIN, OF WATERTOWN, NEW YORK, ASSIGNOR TO INTERNATIONAL BURE
CORPORATION, OF WATERTOWN, NEW YORK.

DEVICE FOR RE-DRESSING SURFACES OF PULP-GRINDSTONES.

1,243,963.

Specification of Letters Patent. Patented Dec. 4, 1917.

Application filed May 5, 1917. Serial No. 166,773.

To all whom it may concern:

Be it known that I, WILLIAM P. AIKIN, citizen of the United States, residing at Watertown, in the county of Jefferson and State of New York, have invented certain new and useful Improvements in Devices for Re-Dressing Surfaces of Pulp-Grindstones; and I do hereby declare the following to be a full, clear, and exact description 10 of the invention, such as will enable others skilled in the art to which it appertains to make and use the same, reference being had to the accompanying drawings, and to the letters and figures of reference marked 15 thereon, which form a part of this specification.

This invention relates to new and useful improvements in devices for re-dressing the surface of pulp grindstones. 20 Heretofore, during the re-dressing operation of a pulp grindstone, the bur was placed in contact with the rotating grindstone, a rotary motion imparted to the bur, the teeth of which produce impressions across the surface of the stone, corresponding to the teeth of the bur used. The burs commonly used are the spiral cut burs, both V-cut and flat bottom, diamond cut burs, thread cut burs and straight cut burs, and it has been found 30 that one of the most successful ways of treating wood pulp grindstones is:

1st—Dress the grindstone with a fine diamond bur, which leaves a surface covered by small teeth, similar to the surface of a coarse file, and doing practically the same work on wood that a file does on iron.

2nd—After this operation is finished, the surface of the grindstone is treated with a spiral bur, which produces impressions 40 across the surface of the stone corresponding to the teeth in the bur, the number of which regulates the grade of pulp desired.

The pulp burs now in use, namely the spiral bur having V-shaped teeth, separated 45 by similar V-shaped channels, when pressed against the grindstone too firmly, breaks the surface of the stone and leaves it unfit to grind a good fibrous pulp. It has also been found that the channels between the teeth of 50 the bur fill up with pieces of stone and slivers of wood, therefore, no very satisfactory results can be obtained by using a bur of this kind. A flat bottom bur is also used which has practically square corners at the

base of the short teeth, but this form of bur 55 has also been found impractical since the flat bottom between the teeth regulates the depth that the teeth on the bur may be pressed into the surface of the grindstone and these burs also, when pressed too firmly 60 against the stone, will bring the flat channels between the teeth in contact with the stone which will tend to roll or crush down the small teeth that were first produced on the stone by the use of the fine diamond bur. 65

My invention consists of an improvement on all burs now commonly made and used, the same having slim V-shaped teeth, separated by any number of round bottom channels, according to the cut of the bur and 70 diameter of the same, whether spiral, straight cut, diamond or thread cut. As can be readily seen by the drawings, there is no possible chance for the round bottom bur to retain any pieces of stone that may break 75 off, or the slivers that always get between the teeth of the bur with square corners, as the round bottom of the bur relieves itself of all substances that tend to pack in and clog. The slim tough round bottom bur will 80 not break the stone like a V-cut bur, nor will it roll the stone like a flat bottom bur, for as soon as the tooth has reached its proper depth, it is brought up against the starting of the round bottom which prevents 85 it from going into the stone farther.

The important feature of the present invention is the provision of a device of this character which will not clog and be rendered temporarily unfit for accomplishing 90 the desired result.

My invention is illustrated in the accompanying drawings, in which:

Figure 1 is an end view of a bur constructed in accordance with the present invention, the bur being shown as operating 95 on a grindstone.

Fig. 2 is a sectional view of the bur.

Reference now being had to the details of the drawings by numeral, 1 indicates a bur 100 which may be hollow or in the form of a solid roller, and is provided with teeth 2 formed on the periphery thereof, the teeth being spaced apart and arranged in any suitable formation, the portions between the 105 teeth or at the base thereof being curved as at 3, whereby all corners and crevices are removed and the possibility of material clog-

ging between the teeth, which would render the bur unfit to accomplish the desired result, obviated.

The bur is also provided with a central bearing 4 in order that the same may be suitably mounted on a rotating shaft.

What I claim to be new is:—

A bur for use in re-dressing the surface of pulp grinding stones, provided with teeth 10 upon its surface, separated by channels the

bottoms of which are concaved to prevent the rolling of the surface of the stone, after being treated, for best results, as set forth.

In testimony whereof I hereunto affix my signature in presence of two witnesses.

WILLIAM P. AIKIN.
